(57) **CLAIM**

The ornamental design for a portable work light stand, as shown and described.

DESCRIPTION

FIG. 1 is a perspective view of a portable work light stand. FIG. 2 is a left side elevational view of the invention.

FIG. 3 is a right side elevational view of the invention.

FIG. 4 is a front elevational view of the invention.

FIG. 5 is a rear elevational view of the invention.

FIG. 6 is a top plan view of the invention; and,

FIG. 7 is a bottom plan view of the invention.

The broken line showing of a light is for illustrative purposes only and forms no part of the claimed design.
